BLANK FOR AN ANIMAL SHOE

Mary C. Henry, 921 S. Lyon St.,
Santa Ana, Calif. 92705

Filed Apr. 15, 1974, Ser. No. 461,161

Term of patent 14 years

Int. Cl. D30—01

U.S. Cl. D30—34

FIG.2

FIG.5

FIG. 1 is a front elevational view of a blank for an animal shoe showing my new design, the rear elevational view being the same with the omission of the tear-drop shaped insole;

FIG. 2 is a top plan view;

FIG. 3 is a left side elevational view;

FIG. 4 is a right side elevational view; and

FIG. 5 is a bottom plan view.

I claim:

The ornamental design for a blank for an animal shoe, as shown and described.
